Patented Nov. 6, 1973

229,113

BED PAN CUSHION COMFORTER OR THE LIKE

Lewis S. Phares, Jr., 12129 Graystone Ave.,
Norwalk, Calif. 90650

Filed June 19, 1972, Ser. No. 264,246

Term of patent 14 years

Int. Cl. D24—99

U.S. Cl. D83—1 V

Fig. 1

Fig. 2

Fig. 3

Fig. 4

FIG. 1 is a perspective view of my new design of a bed pan cushion comforter;

FIG. 2 is a front-elevational view thereof;

FIG. 3 is a rear-elevational view of my present invention; and

FIG. 4 is a bottom plan view thereof.

I claim:

The ornamental design for bed pan cushion comforter or the like, as shown and described.
